FOLDING DISPLAY RACK

Joseph P. Spang, Quincy, Mass.

Application March 27, 1934, Serial No. 717,585

4 Claims. (Cl. 211—149)

This invention relates to a folding display rack and has for its object to provide a novel device of this type which is simple in construction and inexpensive to manufacture and which has various other advantageous features which will be subsequently pointed out.

In the drawings:

Fig. 1 is a perspective view illustrating a folding display rack embodying my invention;

Fig. 2 is a view showing the rack folded;

Fig. 3 is an enlarged section on the line 3—3, Fig. 1 with parts broken out;

Fig. 4 is a fragmentary side view with parts broken out;

Fig. 5 is a fragmentary sectional view showing the upper hinge connection for the end members;

Fig. 6 is a section on the line 6—6, Fig. 4;

Fig. 7 is a sectional view showing the manner of securing the placard-supporting strips in place;

Fig. 8 is a fragmentary top plan view of the back and one end member.

The display rack is of that type which comprises a back member to which shelves are hinged and two end members also hinged to the back member and adapted when in their operative position to support the shelves at the ends but capable of being folded against the back member when the rack is in its folded condition. The back member is constituted by a strip of angle iron which is bent into a general U shape to present the two side portions 1 and 2 and the top or bridge portion 3. The sides 1 and 2 and the top portion 3 are thus integral with each other. This U-shaped angle iron structure is suitably braced by brace members 4 and 5 which cross each other and each of which extends from the top of one side to the bottom of the other side. These brace members are rigidly secured at their ends to the side members 1 and 2 by riveting or spot welding or in any other suitable way. The back is also further braced by a cross brace member 6 which extends between the sides 1 and 2 at their lower end and is riveted or otherwise rigidly secured thereto.

As a further means of bracing and stiffening the back I have provided a plurality of tie rods 7 which extend across the back and through the forwardly-directed legs 8 of the sides 1 and 2. Each tie rod 7 has nuts 9 screw threaded thereto which engage the inner faces of the legs 8, and each tie rod is also provided at each end with a cap nut 10 which is screw threaded thereto and engages the outer face of the leg 8. These tie rods thus serve to stiffen the back and render it more rigid.

The shelves which are pivoted to the back member are shown at 11. Any suitable number of shelves may be employed depending on the size of the cabinet. In the construction herein illustrated there are four such shelves, and, as stated above, these are pivotally connected to the back

member and are adapted to fold downwardly against the back member when the display rack is to be folded.

The shelves 11 are hinged on the tie rods 7, each shelf having secured to its under side a strip 12 that is formed at its end with a loop 13 that encircles the tie rod 7.

The end members which support the shelves in their horizontal or operative position are indicated generally at 14 and 15. Each end member is formed with a front post or leg portion 16, the top cross member 17 and a rear vertically-extending hinge member 18. The leg member 16 and top cross member 17 are integral with each other, they both being formed from a length of angle iron which is bent as shown at 19 to form the vertical leg and the cross member. The vertical leg may be made straight or the upper portion thereof may be inclined rearwardly slightly as shown at 20, the latter being the construction herein shown.

The rear hinge member 18 is in the form of a strip of metal which is spot welded or riveted at its upper end to the rear end of the member 17 and is connected to the front member 16 by 25 means of cross bars 21, said bars also functioning as shelf-supporting bars. These cross bars 21 can be spot welded or riveted to the hinge member 18 and the front leg 16 of the end members thereby making rigid end members of the 30 skeleton type.

The hinge connection between each end member 14 and 15 and the back is constituted by two trunnions 22, 23 formed at the top and bottom of each hinge member 18. The trunnions 22 extend through openings formed in the horizontal leg 24 of the top member 3 of the back as seen in Fig. 5 and the lower trunnions 23 are received in the loops in the bearing brackets 25 which are secured to the inside faces of the forwardly-extending legs 8 adjacent the lower ends thereof. These bearing brackets may be in the form of metal straps which are riveted or spot welded to the legs 8 and the ends of which are bent into loop formation to receive the trunnions. This 45 makes a simple but effective way of connecting the end members 14 and 15 to the back.

Each shelf 11, except the top shelf, is provided at each end with a down-turned lip 26 adapted to embrace the corresponding cross bar 21 as best seen in Figs. 1 and 4, said lips thus not only providing means for supporting the shelf in its horizontal position but by the engagement with the outside of the bars 21 preventing the ends 14, 15 from swinging outwardly. At the front end each shelf 11, except the top shelf, is formed to fit between the rearwardly-extending legs 27 of the front posts 16 as shown in Fig. 3, and when the shelves are in their horizontal or operative position, said shelves co-operate with the end 60

members to hold said members in their shelf-supporting position and to prevent the end members from swinging either inwardly or outwardly.

The top shelf is long enough to rest on and be supported by the horizontal flange 29 of the upper member 17 of each end and the front edge of the top shelf is shown as bent downwardly slightly, as indicated at 28, thereby covering or overlying the corner 19 of the end member.

When it is desired to fold the display rack, the shelves can be swung upwardly sufficiently to disengage the lips 26 from the cross bars 21 and the end members 14 and 15 may then be swung outwardly sufficiently to allow the shelves to drop down into their folded position. After this is done then the end members may be swung inwardly against the folded shelves as shown in Fig. 2 and by the dotted lines in Fig. 3.

The horizontal flanges 19 of the upper member 17 are bevelled so that they are narrower at the rear end adjacent the pintle 22 as shown at 30 in Fig. 8. The rear corner of the top shelf 11 is also bevelled or cut away as indicated at 44 in Fig. 8. The purpose of this is to provide a construction by which a relatively small outward movement of the end member from its normal shelf-supporting position will clear the flange 29 from the top shelf so as to allow the top shelf to be folded downwardly. This is illustrated in Fig. 8 wherein the end member 14 is shown in full lines in its shelf-supporting position and in dotted lines in a position which permits the top shelf to be folded.

When the display rack is to be erected the end members 14 and 15 will be swung outwardly somewhat beyond their normal shelf-supporting position and then the shelves may be swung upwardly, after which the ends may be brought inwardly to a position to permit the lips 26 to be engaged with the cross bars 21. As stated above, when the display stand is erected the co-operation of the shelves with the end members 14 and 15 serve to lock the end members from swinging movement in either direction thereby making a relatively stiff and rigid structure.

32 indicate placard-supporting strips which may conveniently be of metal and which are adapted to be secured to the front posts 16 directly below the front edge of each shelf. Each placard-supporting member is constructed to support a placard which gives some data, such for instance as the price, concerning the articles displayed on the corresponding shelf. These placard-supporting strips 32 are shown as being detachably secured to the posts 16 through suitable fastening devices 33, those herein shown having a head 34 and a bifurcated stem which extends through an opening in the strip 32 and an opening 37 in the front leg 35 of the posts 16, the ends of each part of the stem being bent outwardly as shown at 36. Each placard-supporting strip 32 has portions 38 struck up therefrom which form loops adapted to embrace a placard 39 on which the desired data regarding the articles on display may be printed. These placards can thus be readily changed as the goods on the shelves are changed.

The back of the rack is provided with two uprights or projections 40 which carry an upper placard-supporting member 41, the latter also having the loop portions 42 to receive a placard

43 bearing data descriptive of the goods on display.

When the display stand is to be folded the placard-supporting strips 32 will be removed, the construction of the fastening devices 33 permitting this to be readily done.

I claim:

1. A folding display rack comprising a back member formed from an angle iron bent to present two upright portions and an upper connecting portion, a hinge member secured to the lower end of each upright portion, two end members each having a pintle at its lower end received in the corresponding hinge member and a pintle at its upper end received in an opening in the horizontal flange of the top member of the back, each end member having shelf-supporting bars, and shelves pivoted to the back member, each shelf having at each end a lip to overlie the top and outer face of a shelf-supporting bar. 10

2. A display rack comprising a back member, shelves pivoted thereto to fold downwardly thereagainst, two end members also pivoted to the back member to fold against the folded shelves, each end member having an angle iron front portion, a rear hinge portion and shelf-supporting bars connecting the angle iron front portion and hinge portion, each shelf having at each end a lip to overlie the top and outer face of the corresponding shelf-supporting bar, the front portion of each shelf being confined between the rearwardly-extending legs of the angle iron front portions of the end members, whereby the shelves hold the end members from swinging inwardly and the lips on the shelves not only support the shelves but hold the end members from swinging outwardly. 20

3. A display rack comprising a back member, shelves pivoted thereto to fold downwardly thereagainst, two end members also pivoted to the back member to fold against the folded shelves, each end member having a front post portion, a rear hinge portion and shelf-supporting bars connecting the post portion and the hinge portion, the front portion of each shelf when in operative position being confined between the two post portions and thereby preventing inward swinging movement of said end members, and the ends of the shelves resting on and having interlocking engagement with the shelf-supporting bars and thereby preventing outward swinging movement of said end members. 30

4. A display rack comprising a back member formed from a metal strip bent to present two upright portions and an upper connecting portion, a hinge member secured to the lower end of each upright portion, two end members each having a pintle at its lower end received in the corresponding hinge member, and a pintle at its upper end received in an opening in the upper connecting portion of the back member, each end member having shelf-supporting bars, and shelves pivoted to the back member and adapted to fold downwardly thereagainst, each shelf having at each end a detachable interlocking engagement with the shelf-supporting bar by which the shelf is supported, which interlocking engagement serves to prevent the end member from outward swinging movement. 40

JOSEPH P. SPANG.
